(57) **CLAIM**

The ornamental design for a cable connector for an electronic device, as shown and described.

DESCRIPTION

FIG. 1 is a front, left side perspective view of a first embodiment of a cable connector for an electronic device showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, left side perspective view of a second embodiment of a cable connector for an electronic device showing our new design;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the drawings are directed to environment and form no part of the claimed design.

The broken line break lines in the drawings indicate that the appearance of any portion of the cable connector for an electronic device between the broken line break lines forms no part of the claimed design.

1 Claim, 12 Drawing Sheets
